(57) **CLAIM**

The ornamental design for an electronic nail clipper, as shown and described.

DESCRIPTION

FIG. 1 is front perspective elevational view of an electronic nail clipper showing my new design, shown in environment use;

FIG. 2 is a back, head-on elevational view thereof; and, FIG. 3 is a top plan view thereof.

In the drawings, the broken lines represent portions of the article which form no part of the claimed design.
